UNITED STATES PATENT OFFICE.

WALTER NOAH CLOUSE, OF TIFFIN, OHIO, ASSIGNOR TO THE NATIONAL MACHINERY CO OF TIFFIN, OHIO.

TAP-SOCKET.

1,031,914.

Specification of Letters Patent.

Patented July 9, 1912.

Application filed October 13, 1911. Serial No. 654,531.

To all whom it may concern:

Be it known that I, WALTER NOAH CLOUSE, a citizen of the United States, residing at Tiffin, in the county of Seneca and 5 State of Ohio, have invented a new and useful Tap-Socket, of which the following is a specification.

This invention relates to tap sockets or chucks, and is particularly adapted for use 10 in nut-tapping machines, although it is applicable for various purposes, such as chucks for drills, reamers and similar cutting tools.

The object of this invention is to provide 15 an improved socket to be supported from the spindle of the nut-tapping machine into which the shanks of the taps can be inserted to be securely retained therein and to be revolved with the spindle, and to be raised 20 and lowered with the spindle, as the spindle is moved for the purpose of inserting nuts thereinunder.

Another object is to provide convenient 25 and improved means for removing or inserting a tap from the socket either while the spindle and socket are revolving or while they are at a stand-still, it being necessary at times to remove or insert the tap while the spindle is revolving.

30 A further object is to provide means for automatically ejecting the tap on the same becoming filled with tapped nuts which are allowed to gather thereon by a careless operator of the machine.

35 To the above ends this invention is embodied essentially in a binding ring contained within the socket, through which the shank of the tap is passed upon its being inserted into the socket, which binds the tap 40 in position to prevent the removal thereof, and a slideable sleeve or bushing arranged between the socket and the tap which can be moved to release the said ring to allow the tap to be removed from the socket.

45 The invention is more fully set forth in the following description, it being understood, however that the particular construction of the details may be altered within the scope of the appended claims without 50 departing from the spirit of the invention.

This invention is illustrated in the accompanying drawings, in which similar reference characters indicate similar parts, and in which:—

Figure 1 is a longitudinal central section 55 thereof; Fig. 2 is an enlarged section on the line 2—2 of Fig. 1; and Fig. 3 is a sectional view similar to Fig. 1 of a modified form, parts broken away.

In the drawings, the nut-tapping machine 60 carrying the revolving spindle or spindles has been omitted, these machines being common and the application of this socket thereto being obvious, and for the further reason that this socket may be applied to 65 various other machines and no special machine is essential to its operation.

Referring specifically to the drawings, 9 indicates a cylindrical shell having its upper end open and internally screw 70 threaded and in the lower end thereof a bore or passage 11 therethrough. Into the said screw-threaded end of the shell 9 is engaged the externally screw-threaded head 6 having an upstanding tapered shank 5. 75 This shank is adapted to be engaged into the depending spindle of the nut-tapping machine (not shown) and therefore carries with it, as it is revolved by the spindle, the shell 9. Within the bore 11 slidably fits a 80 bushing or sleeve 10 having the upper flange 12 within the end of the shell 9 and normally resting on the end of the shell, and the lower end thereof protrudes below the end of said shell. The shank 13, which is 85 of the straight shank type, of the tap, drill or reamer is passed through the bushing 10, which bushing serves to center the same. The shank 13 has a flattened end 14 which enters the slot 7 in the head 6 thereby 90 causing the shank 13 to revolve with the spindle. Within the cylindrical shell 9 is arranged a binding-ring 15 the hole of which is of slightly larger diameter than the shank 13. A lug or stud 17 projects into the shell 95 9 from one side thereof and the ring 15 being arranged above the same rests thereon to support one side thereof, and the other side of the same being unsupported falls or drops downward due to the weight thereof. A spirally-coiled spring 16 has its smaller 100 and upper end engaging over the boss 8 on the lower end of the head 6 and the lower end of the same pressing against the upper face of the ring 15 at its periphery to expedite the fall of the unsupported side thereof.

In use, the shank 13 being passed

- through the bushing 10 passes through the ring 15, the flattened end 14 thereof engaging the slot 7 of the head 6, and the ring 15 binds the shank against outward movement.
- 5 Then by pushing the bushing 10 upward the ring 15 is brought to a horizontal position and the shank 13 is free to drop out or be removed. In a nut-tapping machine it is frequent that due to carelessness on the part 10 of the operator thereof the tapped nuts are allowed to fill the shank 13, and if this is the case when this socket is used, the bushing 10 will be automatically raised by the nuts, being pushed upward on the shank 13 and 15 the shank will be ejected or released. The objects aimed at, therefore, are efficiently attained in the above manner.
- In the form shown in Fig. 3 the lug or stud 17 is replaced by a small coiled wire 20 spring 17' which seats at its lower end in the recess 18 in the bottom of the casing 9 and works in a vertical groove 19 in the said casing to resiliently support the binding ring at one side, thus allowing the shank 13 to be 25 withdrawn without raising the bushing 10 if sufficient force is applied to the shank. This is of advantage for the reason that the shank may be released by drawing the same outward against the tension of the spring 30 17', particularly when it is not practical or possible to move the bushing 10 inwardly, and the shank 13 in being drawn outwardly pulls the binding ring therewith, which causes the binding ring to strike the inner 35 end of the bushing and thereby bring the binding ring in a horizontal position to free the shank. The shank may therefore be disengaged by manually drawing the same outwardly, either when at a stand still or when 40 rotating, or the shank may be automatically released by the weight of the nuts accumulating thereon, when the weight of the nuts is sufficient to overcome the tension of the spring 17', as will be understood.
- 45 Having described the invention what is claimed as new is:—
1. A tap, drill or reamer socket comprising a shell, shank engaging means at the upper end thereof, a binding ring in the 50 shell below the said means, and means for supporting the binding ring at one side so that a shank is insertible through the binding ring to be supported thereby and is arranged to be engaged by the shank engaging means to rotate therewith.
  2. A tap, drill or reamer socket embodying a shell, shank engaging means at the upper end thereof, a binding ring within the shell below the said means, means for supporting the binding ring at one side, and a bushing 55 slidble in the lower end of the shell and adapted to strike the binding ring, so that a shank is insertible through the bushing and through the binding ring to be supported thereby and is arranged to be en-
  - gaged by the shank engaging means to rotate therewith.
  3. A tap, drill or reamer socket, comprising a shell, shank engaging means at the upper end thereof, a binding ring in the shell below the said means, means for supporting the binding ring at one side, and a coiled spring pressing against the upper face of the binding ring, so that a shank is insertible through the binding ring to be 75 supported thereby and is arranged to be engaged by the shank engaging means to rotate therewith.
  4. A tap, drill or reamer socket, comprising a shell, shank engaging means at the upper end thereof, a binding ring in the shell below the said means, a spring for resiliently supporting the binding ring at one side, and means at the lower end of the shell against which the said ring is adapted to seat, so that a shank is insertible through the latter means and the binding ring to be supported thereby and is arranged to be engaged by the shank engaging means to rotate therewith.
  5. A tap, drill or reamer socket, comprising a shell, shank engaging means at the upper end thereof, a binding ring in the shell below the said means, a spring for resiliently supporting the binding ring at one side, a coiled spring pressing against the upper face of the binding ring, and means at the lower end of the shell against which the binding ring is adapted to seat, so that a shank is insertible through the latter means and through the binding ring to be supported thereby and is arranged to be engaged by the shank engaging means to rotate therewith.
  6. A tap, drill or reamer socket comprising a shell, shank engaging means at the upper end thereof, a slidble bushing in the lower end thereof, a binding ring in the shell, a coiled spring pressing against the upper face of the binding ring, and means for supporting the binding ring at one side.
  7. A tap, drill or reamer socket comprising a shell, shank engaging means at the upper end thereof, a binding ring in the shell, a spring for resiliently supporting the binding ring at one side, and a bushing slidble in the lower end of the shell and adapted to strike the binding ring, whereby a shank may be passed through the bushing and through the binding ring to be supported thereby and whereby the shank may be released by withdrawing the same outwardly against the tension of the said spring.
  8. A tap, drill or reamer socket, comprising a shell, shank engaging means at the upper end thereof, a binding ring in the shell, a coiled spring for resiliently supporting the binding ring at one side, a coiled spring pressing against the upper face of the binding ring, and a bushing slid- 130

able in the lower end of the shell and adapted to strike the binding ring, whereby a shank may be inserted through the said bushing and through the binding ring to be supported thereby and whereby the shank may be released by withdrawing same against the tension of the former spring.

In testimony that I claim the foregoing as my own, I have hereto affixed my signature in the presence of two witnesses.
